BREAD WRAPPING MACHINE

Lester Ferenci, Brooklyn, N. Y., assignor to American Machine & Foundry Company, a corporation of New Jersey

Application May 5, 1934, Serial No. 724,151

48 Claims. (Cl. 93—2)

This invention relates to wrapping machines and more particularly to bread wrapping machines of the general type disclosed in my prior Patent No. 2,082,945, issued June 8, 1937.

5 One of the principal objects of the invention is to provide means whereby adjustable tension can be applied to the wrapper as the wrapper is applied to the article or loaf, permitting the selection of a loosely or tightly wrapped package 10 or some intermediate tightness thereof.

Another object of the invention is to improve the action and construction of the rod which lays or drapes the wrapper along one side of the article and to some extent determines the tightness of 15 the wrapper. To this end, this rod is mounted for free floating movement in vertical direction and rests by gravity on the portion of the wrapper on which it is intended to act. Thus the wrapping tension produced by this rod may be 20 varied by simply changing its weight. Also by limiting the lower movement of the rod at different points, it is possible to secure an adjustment for loaves of different height, with the object of having the wrapper draped under tension 25 as low along the side of the loaf as possible when rear side tucks are being made. For the purpose 30 of simplifying the rod operating means, as stated, the rod is operated by gravity, instead of by linkage from a cam as formerly, and the movement 35 of the rod at the upper limit of its motion where it is desired to positively actuate the same, is produced by a projecting portion carried by the lifter table.

Another object of the invention is to produce 35 improved clamping and tensioning structure controlling the last folded end of the wrapper. To this end a clamp for holding this end of the wrapper stationary during part of the wrapping operation is controlled by the draping or lapping 40 rod above referred to, as actuated by the lifter table.

Another object of the invention is to prevent 45 slippage of the wrapper between the back tension plate and the article fed against the wrap- 50 per and tension plate to produce a uniform lap on the under side of the package and to make the resistance of this tension plate variable to fit varying conditions.

Another object is to seal the overlapping por- 55 tions of the wrapper while the wrapper is still under tension after being wrapped around the article, without relying on the mere friction of the wrapper as it is pushed along a table, to retain said tension.

Still another object is to simplify adjusting the

machine for different widths of loaves or articles by so connecting the side guide plates on a moving lifter table with the side guide plates on a stationary feedway of the machine, that adjustment of one set of plates will automatically adjust the other set of plates, without interfering with the up and down movement of the lifter table. Other objects are to provide means for preventing over-running of the feed roll and to provide a simple and efficient means for taking care of crumbs. 5

With these and other objects not specifically mentioned in view, the invention consists in certain constructions and combinations which will be hereinafter fully described and then particularly pointed out in the claims hereunto appended. 15

In the accompanying drawings which form a part of this specification and in which like characters of reference indicate the same or like parts: 20

Fig. 1 is a side elevation, partly in section, showing the progress of a loaf of bread from the intake conveyor onto a lifter and raised to the level of the slicer, then pushed onto a second lifter and raised to the delivery level; 25

Fig. 2 is a sectional end elevation, partly in section from the right of Fig. 1;

Figs. 3 to 7 inclusive are detail views in side elevation showing the progressive stages of a loaf wrapped in the machine shown in Fig. 1; 30

Fig. 8 shows a large scale side view of the friction device for the tension plate;

Fig. 9 is a cross-section on line 9—9 of Fig. 8;

Fig. 10 is an enlarged detail side view of braking device for the wrapper material reel, shown 35 in Fig. 3;

Fig. 11 is an end view of the parts shown in Fig. 10;

Fig. 12 is a detail sectional side view showing the lifter with a partially enfolded loaf at the 40 delivery level, showing tight and loose wrap mechanism, positioned to produce a tightly wrapped package;

Fig. 13 is a view similar to Fig. 12, showing the tensioning device in non-operative position in 45 order to produce a "loosely" wrapped package;

Fig. 14 is a plan view of Fig. 13;

Fig. 15 is a detail view in section on line 15—15 of Fig. 14, showing an electric heating cartridge mounted under the front end of the delivery 50 table;

Fig. 16 is a detail view in end elevation of a braking device for the roller which clamps the end of the wrapper material;

Fig. 17 is an enlarged detail in side view (partly 55

in section) showing some operating parts of wrapper material feed;

Fig. 18 is a sectional side view showing additional parts of the feed shown in Fig. 17;

5 Fig. 19 is a sectional side view (from the opposite side to that shown in Fig. 17), of the wrapper feed shown;

10 Fig. 20 is a sectional side view of a detail of Fig. 19 showing the feed rollers in "released" position.

15 While the invention is shown in conjunction with the machine illustrated in my prior patent referred to above it will be understood that its usefulness is not limited to such machines, as it may be applied to other types of wrapping machines.

20 Referring to the drawings, Figs. 1 and 2, a loaf L is shown on the feed conveyor table 89 about to be transferred to a lifter table 57 and raised by lifter 58 to the level of the transfer or slicer table 83.

25 As the top loaf is transferred to lifter table 57 the ends of the loaf enter between guide plates 351 and 352. These guide plates are each attached to two rods 353 and 354 which are slidably mounted in guide brackets 355 and 356 respectively. As the lifter 58 raises the loaf L on plate 57 to the level of table 83 the guide plates 351 and 352, which rest on table 57 through rollers 357 and 358, move up with the lifter, causing rods 353 and 354 to slide up through bearings in brackets 355 and 356, thus holding the loaf L securely while in transit. Brackets 355 and 356 are attached to bars 268 which also carry end guides 328 on the delivery level and when these guides are being adjusted, to suit the length of loaf L, guide plates 351 and 352 are automatically set to the proper spacing on lifter table 57. A small independent adjustment to the guide plates 351 and 352 can be made, if necessary, by shifting the plates, in or out, on rods 353 and 354.

30 When the loaf has been pushed off the lifter table 57 and the lifter moves down to the intake conveyor level, the end guides 351 and 352 with rods 353 and 354 follow the lifter by gravity or, if desirable, springs (not shown) may be attached to the rods, inside of brackets 355 and 356, to assist the downward movement.

35 As the loaf is being pushed off the lifter table 57 it enters between end guides 84 and as it is pushed across transfer table 83 it may be sliced or passed whole across and onto a second lifter 108.

40 When the loaf enters the lifter 108 it carries with it the wrapper material W, one end of which has been brought down by lifter 108, as indicated in Fig. 4, thus starting the wrapping operation as shown in Fig. 5.

45 It will be noted that the floating rod 313 begins to function at this stage by holding back on the wrapper W while the loaf L advances. The lifter 108 is now ready to move up to the delivery level, and, while in transit, the wrapper W acted upon by floating rod 313 is draped down over the top 50 of the loaf L as indicated in Fig. 6. The wrapper W is thus subjected to the weight of floating rod 313, thereby keeping the wrapper tight while it is being enfolded about the loaf.

55 Just before the lifter reaches the delivery level, lugs 108a on the lifter contact with floating rod 313 and carry it along. Rod 313 in turn contacts with the forked ends 314a of a plurality of clamping levers in each of which is journaled a clamping roller 315, whereby the rollers 315 are lifted 60 and the free end of the wrapper W is released

from the grip of rollers 315 and 316, as shown in Fig. 7.

65 The loaf, not yet completely wrapped, is now in a position to be pushed onto the delivery table 221 where the wrapping is completed after the lifter 108 has been lowered sufficiently for tension plate 312 to clear pusher 223. When the pusher 70 halts in the position shown in Fig. 3, the lifter 108, which has previously raised the loaf to the position indicated by dotted lines, descends to resume its position at the level of transfer table 83 ready to receive the next loaf, as shown in Fig. 1 and indicated by dotted lines in Fig. 3.

75 If it is not desired to have the loaf "tightly" wrapped the pusher 223 proceeds to move the loaf along, thus finishing the wrapping operation with only the drag due to friction of the free end of the wrapper as the loaf is being pushed over the delivery table 221.

80 If a tighter wrapped package is preferred a special drag device can be put into action, as shown in Fig. 12, by setting quadrant 341 so as to obtain the desired pressure of drag levers 342, by means of leaf springs 343 bearing on pins 342b thereof, against the drag rollers 344. As the wrapper W passes between drag levers 342 and rollers 344 it will be subjected to this drag during the last stage of the wrapping operation after rollers 315 and 316 have released their grip. Thus the amount of pressure exerted by the springs 343 can be adjusted by setting the quadrant. When this final tight wrapping operation is not desired the quadrant may be set, as shown in Fig. 13, to maintain the drag levers in non-operative position wherein the springs 343 bear 85 against pins 342a on drag levers 342, thus keeping them away from rollers 344.

90 When using heat sealable regenerated cellulose as wrapping material it is desirable to apply heat in order to seal the overlapped wrapper edges forming the bottom seam as the package enters the delivery table 221 (see Fig. 3). This feature of sealing the bottom seam insures that the outer edge of the regenerated cellulose will not be pulled away from the loaf while it is being pushed along 95 the delivery table. For this purpose a cartridge type electric heater H is mounted under the front end of the delivery table as shown in Figs. 14 and 15.

98 The tension plate 312 is slidably mounted on the lifter 108 and its movement is controlled by friction so that the push of the oncoming loaf L makes it recede, yet producing enough resistance to securely grip the wrapper W while the loaf enters between the tuckers 208 and the first end 105 folds are being made (see Fig. 5). The wrapper is thus held while it is being drawn over the top of the loaf and the side remote from the tension plate, as illustrated in Fig. 5. As the lifter brings the loaf up to the delivery level the top end flaps 110 of the wrapper are folded down over the end of the loaf by stationary folders (not shown), and as it is pushed along the delivery table the front and bottom end flaps are folded over the end of the loaf, as disclosed in my co-pending patent application previously mentioned. Fig. 7 indicates the step of folding the top end flaps but the folder structure for this operation and the subsequent folding operations are not shown since they are disclosed in the above mentioned application.

110 The tension plate 312 has, on its face, several horizontal grooves 312a which assure a secure grip on the wrapper and the loaf while it is in transit up to the level of the delivery table. The movement of the tension plate may be controlled

by a friction device. One object of the friction device is to avoid any spring means for returning the tension plate, and to leave this function entirely to the motion of the pushers which push 5 the loaf onto and off the lifter 108.

The friction device, as shown in Figs. 8 and 9, consists of a tension plate carrier 321 mounted in ways of the guide rails 322, a bolt 323, two 10 friction washers 324a and 324b, one on each side of a stationary slotted drag strip 325 carried by the lifter, the coil spring 326 being interposed between top friction washer 324a and adjusting nut 327. The desired amount of friction is obtained by setting up nut 327, to compress spring 15 326 to produce the required pressure or drag on strip 325.

In order to prevent over-travel of wrapping material W due to the inertia of the reel R, as 20 the wrapping material is being unwound, a friction brake of the torsion type is attached to the reel shaft R', as shown in Figs. 3, 10 and 11. The brake consists of a clamp having hinged jaws 331a and 331b, the jaw 331a carrying a leaf spring 332 which abuts on a stud 333 set into the 25 frame F of the machine. The inner faces of the clamp jaws are provided with a suitable brake lining 334, and the proper friction is obtained by tightening screw 335 and thus compressing spring 336 to produce the required pressure on 30 the reel shaft.

When the reel R starts to rotate, as the material W is being "fed-off", the brake clamp will turn with the reel causing the spring 336 to deflect until its resistance is sufficient to overcome 35 the friction of the brake on the reel shaft, and as the feed stops the springs 336 will tend to resume its original shape and in doing so it will rotate the reel R, in opposite direction to the feed, sufficiently to recover any slack that may have 40 been caused by the inertia of the rotating reel.

The wrapper material W is fed from the reel R over the feed roller 120 mounted on shaft 122 in brackets 123 attached to side frames 20 and 21 as shown in Figs. 1 and 3. Gear 160 on shaft 45 122, Fig. 19, engages gear 159 on shaft 158 on which are also mounted feed traction rollers 121. On the opposite end of shaft 122 is a gear 127, Fig. 17, engaging gear 128 which is mounted on the hub of gear 131 which is free to turn on shaft 50 129. Gear 131 is actuated by a rocking gear segment 132 which is pivoted on stud 133. Segment 132 has an arm 134 which, through rod 135, is connected with lever 136, on shaft 137 in bearings on side frames 20 and 21.

Lever 139, attached to shaft 137, is connected 55 through rod 140 to the main drive mechanism of the machine which operates as disclosed in my prior patent previously referred to.

As the drive mechanism pulls rod 140 in the 60 direction indicated by the arrow in Fig. 17, it imparts, through the connections just described, a swinging motion to arm 134 and segment 132, which, in turn, causes gear 131 to rotate on shaft 129.

The hub of gears 131 and 128 are designed to 65 constitute a "one-way" clutch of the well known jam roller construction, so that gear 131 can impart rotation to gear 128 in one direction only; thus, while segment 132 swings in the direction 70 indicated by arrow, Fig. 17, gear 131 will rotate gear 128, but on the reverse swing of segment 132 the clutch will release gear 131 from gear 128 and gear 131 will rotate free on shaft 129, and will impart no motion to gear 128, until segment 75 132 has again reversed its direction of motion.

The feeding of wrapper material W is therefore accomplished while segment 132 swings in the direction indicated by arrow in Fig. 17 and rotates gear 131 which, through "one-way" clutch, is locked to gear 128. Gear 128 engages gear 127 5 on shaft 122 and gear 160 on the other end of shaft 122, Fig. 19, engages gear 159 on shaft 158 which also carries feed rollers 121. For each swing of segment 132, in the direction just described, the feed rollers 121 are made to rotate 10 and as the wrapper web W has been passed between roller 120 and feed rollers 121 an amount of wrapper web is fed off the reel R for each "one-way" swing of segment 132. The web W, as it is pushed along horizontally enters the guide 15 channel formed by a shelf 108b on lifter 108, which is then in a position as indicated in Fig. 3, and passes over rollers 316. When a predetermined amount of web has been advanced it is cut off and, as the lifter 108 starts down, roller 20 315 drops and pinches or clamps the web against roller 316, thus holding the forward end of the web securely while the lifter carries the remainder of the web down with it and spreads it ready to receive the oncoming loaf L as indicated in 25 Fig. 4.

In order to prevent over-travel of the wrapper feed mechanism, shown in Fig. 17, after segment 132 has completed the necessary feeding motion, a brake shoe 361a on brake lever 361 is brought 30 to contact with the feed roller 120, thus holding the feed mechanism between the reel R and the gear 131 stationary, until segment 132 has started on its reverse swing. The brake lever 361, pivotally mounted on shaft 164, is operated by rod 35 362, the lower end of which is connected to lever 136 at 136a and the upper end passing freely through the end 361b of lever 361 until the swing of lever 136 has been almost completed and the space between spring 362b and the adjustable 40 lock-nuts 362a has been taken up. The spring 362b will then bring the necessary pressure to bear on brake lever 361 to hold feed roller 120 immovable.

As safeguard against any motion to disturb 45 the feed mechanism in the opposite direction to the feed, when segment 132 reverses its direction of swing, an arcuate anti-backing wedge 363, Fig. 18, pivotally mounted on shaft 164 and held against feed roller 120 by spring 364, is in 50 a position to jam against the roller and instantly check any attempt of roller 120 to rotate in a direction opposite to the feed.

The shaft 158 with feed rollers 121 is mounted in brackets 161 which are pivoted on shaft 129, 55 as shown in Figs. 19 and 20. If lever 165, on shaft 164 is thrown over, as indicated by dotted lines in Fig. 19, cams 163 are brought to bear on extensions 162 of brackets 161 causing rollers 121 on shaft 158 to be swung away from contact 60 on roller 120. This arrangement is provided for convenience in threading the web through the machine and is also useful in stopping the feed of wrapper web W, if desired, without shutting off the drive mechanism.

A rod 365 which is hooked onto shaft 164 and passes through bracket extension 162 and a spring 366, is interposed between extension 162 and nuts 367 and permits of adjusting the pressure 65 on the wrapper web W between feed rollers 121 and roller 120.

In order to prevent roller 316 from overrunning, thereby reducing the amount of tension on the wrapper and also to regulate this tension to that found most satisfactory for the use to which 75

the machine is being put and in accordance with whether a tight or loose wrap is desired, a friction device has been introduced which consists of roller sleeve 316, as shown in Fig. 16, mounted 5 on shaft 316a, which is held in side frames 20 and 21, being secured from rotation in side frame 20. A spring 316b interposed between sleeve 316c and adjusting nut 316d exerts pressure between non-rotating sleeve 316c and friction bushing 10 316e at one end of roller 316. Friction bushing 316f, at the other end of roller 316, bears against collar 316g on shaft 316a.

By adjusting nut 316d, a suitable pressure can be produced by spring 316b to keep roller 316 15 from rotating except as the wrapper web W is being dragged out of the grip between rollers 316 and 315 by the pull on the web as the loaf is pushed into it, and this pull can be made greater or less as desired.

20 A trough 368, Figs. 1 and 2, is positioned under the intake or feed conveyor for the purpose of supporting the chains and pushers and it also serves the purpose of catching any crumbs that may drop from the loaves as they are being conveyed in on top of conveyor table 39. The pusher bars 47 will sweep them along the trough 368 and at the end of the trough they may be collected in a suitable receptacle.

The loaves lifted by the lifter table 57 to the 25 level of the runway 83 are pushed off the table 57 by a pusher 370. This pusher has a suitable guide portion forming the shank of the pusher 370 which slides on rails 372. The guide portion carries a rearwardly extending rack 373 which 30 engages an oscillating gear 374 on a shaft 375. The pusher 370 is suitably slotted to admit slicer blades when used in conjunction with slicer mechanism and has a stroke sufficient to carry the loaves across the runway 83 and onto the 35 lifter table 108 serving to push the loaf into the wrapper W (Figs. 4 and 5), and against the back tension plate 312.

While the invention has been described for 40 illustrative purposes in connection with the bread wrapping machine disclosed in my patent previously identified, the invention is not to be taken as being limited to bread wrapping since it may be used to wrap cartons and other articles nor are many of the features to which the invention 45 relates limited to wrapping in waxed paper or paper only, since it is contemplated that the invention may be used in connection with regenerated cellulose and other wrapping materials. It is also to be understood that a number of the 50 improvements described can be employed alone or in widely different types of wrapping machines and are not limited to use in the type of wrapping machine and the particular combinations selected for illustration. Thus the apparatus 55 employed in carrying the invention into effect may be widely varied in construction within the scope of the claims for the specific structures selected to illustrate the invention are but certain of many possible embodiments of the same. The invention therefore is not restricted to the details illustrated and described nor to the particular embodiments chosen as illustrative of the invention.

The operation of the machine illustrated has 60 already been described in connection with the description of its parts, but for greater clearness it is reviewed and in certain respects amplified below.

As previously noted, the loaf L is pushed into 65 the wrapper W (Figs. 1, 4 and 5), and against

the back tension plate 312 so that the wrapper is clamped between the plate and the loaf. The portion of the wrapper depending below the tension plate at this moment determines the position of the lapping edge of this end of the wrapper 70 and so affects the appearance of the package. For the purpose of obtaining a uniform position of this lapping end, it is important that there may be no slip between the loaf and the tension plate of the wrapper and for preventing this the tension plate is grooved to provide a serrated or ribbed surface. Also the resistance of the tension plate is regulated by friction brake means 75 as already described, controlling the pressure between the plate and the loaf which must be less than that which would collapse soft loaves but may be made greater with firm loaves and particularly cartons and other sturdier objects which are to be wrapped.

As the article to be wrapped is carried on to 20 the lifter table the surplus material necessary to enwrap the article will be dragged from between the rollers 315 and 316 and the force needed to drag this material out is regulated by the 25 brake 316c operating on the roller 316. These rollers may of course be solid rods and not necessarily round rods, the object of using rollers being merely to avoid accumulations of wax, when waxed paper is used, at one point. After the wrapper has been folded around the bottom, rear 30 (or left hand side as shown in Figs. 1, 4 and 5), and part of the top side, the front side and the remainder of the top side has the wrapper draped around it under the influence of the rod 313 which 35 rests by gravity on the portion of the wrapper between the clamp rollers 315 and 316 and the side of the article so that the roller forms a loop in the wrapping material, as shown in Fig. 6. One of the advantages of this arrangement is that a predetermined constant tension is placed upon the wrapper during its draping action down along the front side of the article 40 determined by the weight of the rod 313 which weight may be easily changed by merely substituting a rod of a different weight. This arrangement also simplifies the machine for the reason that no line of linkage to an operating cam is needed for operating said rod. Similarly 45 the machine is considerably simplified by utilizing a projection on the lifter table acting 50 through this rod to lift the clamp roller 315 as a result of the motion already present of the lifter table without the addition of operating linkage.

The inter-action of the clamp roller 315 and 55 the rod 313 provides a desirable equalized tension on this end of the wrapper. Near the end of the upper movement of the article but before the rod is engaged by the projection 108a on the lifter table the rod is pulled by the wrapper web 60 tension into engagement with the lever 314 thus momentarily lifting clamp roller 315. The moment this clamp roller is released some of the 65 wrapper is withdrawn permitting dropping of the rod 313, again placing tension on the wrapper so that at no time is the tension released until the wrapper end is in the range of action of the clamping or tensioning parts 342 and 344.

It is an advantage, well understood in the 70 wrapping art to have one fold as nearly completed as possible before another fold is made since production of the second fold tends to disturb the first. For this reason it is desirable that the rod 313 be permitted to hold the wrapper as low alongside the loaf, that is, as nearly com- 75

pletely folded about the loaf as possible, at the time the tucker 208 breaks in the wrapper end fold as shown in Fig. 5. For this reason the guides 313a having the vertical slots 313b in which the ends of the rod 313 is mounted for floating gravity movement are provided with graduated holes 313c, in which a pin 313d can be adjustably positioned to limit the movement of the rod to a lower position under which the highest loaf to be wrapped may pass.

What is claimed is:

1. The combination with a delivery table, of a vertically reciprocable lifter movable up to and down from the level of said table, a guide on said lifter adapted to support a wrapper, a yielding tension plate slidably mounted on said lifter, a pair of spaced tuckers on said lifter, stationary rollers beneath said table, clamp levers provided with clamping rollers coacting with said stationary rollers to clamp the end of a wrapper projecting from said guide, whereby the wrapper is partially withdrawn from said guide during the descent of said lifter so that an article may be pushed, with the portion of the wrapper thus withdrawn, between said tuckers and against said tension plate to partially enfold the article in the wrapper, a floating rod arranged to bear down on the wrapper adjacent its clamped end and thus drape the wrapper down over the article during the ascent of said lifter, vertical guides for said rods, lugs on said lifter adapted to raise said rod against said clamp levers to lift them from said stationary rollers during the ascent of said lifter, a reciprocable pusher arranged to push said tension plate to deliver the partially enfolded article to said table and cause the free end of its wrapper to be wiped under the bottom of the article, drag rollers on said lifter above said guide, drag levers adjacent said table, an adjustable quadrant, and leaf springs carried by said quadrant and urging said drag levers against said drag rollers to exert a drag on the free end of the wrapper while the partially enfolded article is being delivered to said table, whereby the wrapper is "tightly" enfolded about the girth of the article.

2. The combination with a delivery table, of a vertically reciprocable lifter movable up to and down from the level of said table, a guide on said lifter adapted to support a wrapper, a yielding tension plate slidably mounted on said lifter, a pair of spaced tuckers on said lifter, stationary rollers beneath said table, clamp levers provided with clamping rollers co-acting with said stationary rollers to clamp the end of a wrapper projecting from said guide, whereby the wrapper is partially withdrawn from said guide during the descent of said lifter so that an article may be pushed, with the portion of the wrapper thus withdrawn, between said tuckers and against said tension plate to partially enfold the article in the wrapper, a floating rod arranged to bear down on the wrapper adjacent its clamped end and thus drape the wrapper down over the article during the ascent of said lifter, vertical guides for said rod, lugs on said lifter adapted to raise said rod against said clamp levers to lift said clamping rollers during the ascent of said lifter, a reciprocable pusher arranged to push said tension plate to deliver the partially enfolded article to said table and cause the free end of the wrapper to be wiped under the bottom of the article, drag rollers on said lifter above said guide, drag levers adjacent said table, an adjustable quadrant, and leaf springs carried by said quadrant and urging said drag levers against said drag rollers to exert

a drag on the free end of the wrapper while the partially enfolded article is being delivered to said table whereby the wrapper is "tightly" enfolded about the girth of the article, said lifter being provided with guide rails and a stationary slotted drag strip, and said tension plate being provided with a carrier slidably mounted in said rails, a friction washer mounted on said bolt and bearing against one side of said strip, a nut threaded on said bolt, and a spring interposed between said nut and washer.

3. The combination with a delivery table, of a vertically reciprocable lifter movable up to and down from the level of said table, a guide on said lifter adapted to support a wrapper, a yielding tension plate slidably mounted on said lifter, a pair of spaced tuckers on said lifter, stationary rollers beneath said table, clamp levers provided with clamping rollers coacting with said stationary rollers to clamp the end of a wrapper projecting from said guide, whereby the wrapper is partially withdrawn from said guide during the descent of said lifter so that an article may be pushed with the portion of the wrapper thus withdrawn between said tuckers and against said tension plate to partially enfold the article in the wrapper, a floating rod arranged to bear down on the wrapper adjacent its clamped end and thus drape the wrapper down over the article during the ascent of said lifter, vertical guides for said rod, lugs on said lifter adapted to raise said rod against said clamp levers to lift said clamping rollers during the ascent of said lifter, a reciprocable pusher arranged to push said tension plate to deliver the partially enfolded article to said table and cause the free end of the wrapper to be wiped under the bottom of the article, whereby the wrapper is "loosely" enfolded about the girth of the article.

4. The combination with a delivery table, of a vertically reciprocable lifter movable up to and down from the level of said table, a guide on said lifter adapted to support a wrapper, a yielding tension plate slidably mounted on said lifter, a pair of spaced tuckers on said lifter, stationary rollers beneath said table, clamp levers provided with clamping rollers coacting with said stationary rollers to clamp the end of a wrapper projecting from said guide, whereby the wrapper is partially withdrawn from said guide during the descent of said lifter so that an article may be pushed with the portion of the wrapper thus withdrawn between said tuckers and against said tension plate to partially enfold the article in the wrapper, a floating rod arranged to bear down on the wrapper adjacent its clamped end and thus drape the wrapper down over the article during the ascent of said lifter, vertical guides for said rod, lugs on said lifter adapted to raise said rod against said clamp levers to lift said clamping rollers during the ascent of said lifter, a reciprocable pusher arranged to push said tension plate to deliver the partially enfolded article to said table and cause the free end of the wrapper to be wiped under the bottom of the article, whereby the wrapper is "loosely" enfolded about the girth of the article, said lifter being provided with guide rails and a stationary slotted drag strip, and said tension plate being provided with a carrier slidably mounted in said rails, a bolt on said carrier fitted into the slot of said strip, a friction washer mounted on said bolt and bearing against one side of said strip, a nut threaded on said bolt, and a spring interposed between said nut and washer.

5. The combination with a vertically reciprocable lifter, of a guide on said lifter adapted to support a wrapper, a yielding tension plate slidably mounted on said lifter, stationary rollers adjacent the upper position of said lifter, levers provided with clamping rollers coacting with said stationary rollers to clamp the end of a wrapper projecting from said guide, whereby the wrapper is partially withdrawn from said guide 10 during the descent of said lifter so that an article may be pushed, with the portion of the wrapper thus withdrawn, against said tension plate to partially enfold the article in the wrapper, a floating rod arranged to bear down on 15 the wrapper adjacent its clamped end and thus drape the wrapper down over the article during the ascent of said lifter, vertical guides for said rod, lugs on said lifter adapted to raise said rod against said clamp levers to lift said clamping 20 rollers from said stationary rollers during the ascent of said lifter, drag rollers on said lifter above said guide, drag levers adjacent the upper position of said lifter, an adjustable quadrant, and leaf springs carried by said quadrant and 25 urging said drag levers against said drag rollers to exert a drag on the free end of the wrapper as it is drawn between said drag rollers and drag levers.

6. The combination with a vertically reciprocable lifter, of a guide on said lifter adapted to support a wrapper, a yielding tension plate slidably mounted on said lifter, stationary rollers adjacent the upper position of said lifter, levers provided with clamping rollers coacting with 30 said stationary rollers to clamp the end of a wrapper projecting from said guide, whereby the wrapper is partially withdrawn from said guide during the descent of said lifter so that an article may be pushed, with the portion of the wrapper thus withdrawn, against said tension plate to partially enfold the article in the wrapper, a floating rod arranged to bear down on the wrapper adjacent its clamped end and thus drape the wrapper down over the article during the ascent 35 of said lifter, vertical guides for said rod, lugs on said lifter adapted to raise said rod against said clamp levers to lift said clamping rollers from said stationary rollers during the ascent of said lifter, drag rollers on said lifter above said guide, drag levers adjacent the upper position of said lifter, an adjustable quadrant, and leaf springs carried by said quadrant and urging said drag levers against said drag rollers to exert a drag on the free end of the wrapper as it is drawn 40 between said drag rollers and drag levers, said lifter being provided with guide rails and a stationary slotted drag strip, and said tension plate being provided with a carrier slidably mounted in said rails, a bolt on said carrier fitted into the slot of said strip, a friction washer mounted on said bolt above said strip, a nut threaded on said bolt, and a spring interposed between said nut and washer.

7. The combination with a vertically reciprocable lifter having a guide adapted to support a wrapper, of stationary rollers adjacent the upper position of said lifter, clamping levers provided with clamping rollers coacting with said stationary rollers to clamp the end of a wrapper projecting from said guide, whereby the wrapper is partially withdrawn from said guide during the descent of said lifter so that an article may be pushed into the portion of the wrapper withdrawn and onto said lifter to partially enfold 75 the article in the wrapper, a floating rod ar-

ranged to bear down against the clamped end of the wrapper during the ascent of said lifter, vertical guides for said rod, lugs on said lifter adapted to raise said rod against said clamping levers to lift said clamping rollers from the 5 wrapper during the ascent of said lifter, drag rollers on said lifter, drag levers adjacent the upper position of said lifter, an adjustable quadrant, and leaf springs carried by said quadrant urging said drag levers against said drag rollers as it is drawn between said drag rollers and levers. 10 8. The combination with a lifter adapted to receive an article and raise it to a higher level, a guide on said lifter adapted to support a wrapper, stationary rollers, levers provided with clamping rollers coacting with said stationary 15 rollers to clamp the end of a wrapper projecting from said guide, a floating rod arranged to bear down on the wrapper adjacent its clamped end 20 during the ascent of said lifter, guides for said rod, and lugs on said lifter adapted to engage and raise said rod against said levers to lift said clamping rollers from the wrapper during the ascent of said lifter. 25

9. The combination with a lifter adapted to receive an article and raise it to a higher level, a guide on said lifter adapted to support a wrapper, stationary rollers, levers provided with clamping rollers coacting with said stationary 30 rollers to clamp the end of a wrapper projecting from said guide, a floating rod arranged to bear down on the wrapper adjacent its clamped end, and guides for said rod. 35

10. The combination with a lifter adapted to receive an article and raise it to a higher level, a guide on said lifter adapted to support a wrapper, stationary rollers, levers provided with clamping rollers coacting with said stationary 40 rollers to clamp the end of a wrapper projecting 45 from said guide, a floating rod arranged to bear down on the wrapper adjacent its clamped end, vertical guides for said rod, lugs on said lifter adapted to engage and raise said rod against said levers to lift the clamping rollers from the wrapper during the ascent of said lifter, a reel shaft adapted to support a reel of wrapping material, a support for said shaft, a pair of intermittently operating feed rollers coacting to draw the web of wrapping material off said reel and feed it 50 through said guide between said stationary and clamping rollers while the latter are lifted, a torsion brake on said shaft opposing the rotation thereof in the direction of web feed, and operative to rotate said shaft in the opposite direction 55 after cessation of the web feed and thereby recover any slack in the web caused by the inertia of the reel, and a knife for severing a wrapper from the web.

11. The combination with a lifter adapted to receive an article and raise it to a higher level, a guide on said lifter adapted to support a wrapper, stationary rollers, levers provided with clamping rollers coacting with said stationary 60 rollers to clamp the end of a wrapper projecting 65 from said guide, a floating rod arranged to bear down on the wrapper adjacent its clamped end, vertical guides for said rod, lugs on said lifter adapted to engage and raise said rod against said levers to lift the clamping rollers from the wrapper during the ascent of said lifter, a reel shaft adapted to support a reel of wrapping material, a support for said shaft, a pair of intermittently 70 operating feed rollers coacting to draw the web of wrapping material off said reel and feed it 75

through said guide between said stationary and clamping rollers while the latter are lifted, a torsion brake on said shaft opposing the rotation thereof in the direction of web feed, and operative to rotate said shaft in the opposite direction after cessation of the web feed and thereby recover any slack in the web caused by the inertia of the reel, and a knife for severing a wrapper from the web, said brake including a clamp having hinged jaws, a screw threaded into said jaws and provided with a head, a coil spring interposed between one of said jaws and the head of the screw, a stationary stud, and a leaf spring carried by the other of said jaws and abutting 15 said stud.

12. The combination with an article lifter, of a tension plate on said lifter, said lifter being provided with guide rails and a stationary slotted drag strip, and said tension plate being provided with a carrier slidably mounted in said rails, a bolt on said carrier fitted into the slot of said strip, a friction washer mounted on said bolt and bearing against one side of said strip, a nut threaded on said bolt, and a spring interposed 20 between said nut and washer.

13. In a wrapping machine, the combination with an article lifter, of means coacting with said lifter to drape in succession each of a series of sections of wrapping material about its appropriate article, said means including an element positioned alongside said lifter to lay the wrapper alongside of the article, said element being mounted for free vertical movement by gravity along the path of said lifter, and means for moving 25 said rod intermittently into position to be engaged with each wrapper section in turn.

14. In a wrapping machine, the combination with an article lifter, of means coacting with said lifter to drape a wrapper about the article, including a rod positioned alongside said lifter to lay the wrapper alongside of the article, said rod being mounted for free vertical movement along the path of said lifter, and means on the lifter for imparting movement to the rod.

15. The combination with a lifter adapted to receive an article and raise it to a higher level, of means for draping a wrapper over said article including mechanism for clamping one end of said wrapper, and a floating rod arranged to rest by gravity on the wrapper adjacent its clamped 45 end to yieldingly hold the paper down adjacent one side of the article being lifted, and guides for guiding the same in a path extending along the path of movement of the article on the lifter.

16. In a wrapping machine, the combination with means for clamping a wrapper sheet near one edge, of an article lifter for lifting an article to be wrapped into said sheet, a floating element resting on the wrapper between the article and said clamp for carrying the wrapper down along the adjacent side of the wrapper as the article is lifted alongside the same.

17. In a wrapping machine, the combination with means for clamping a wrapper sheet near one edge, of an article lifter for lifting an article to be wrapped into said sheet, a floating rod resting on the wrapper between the article and said clamp for carrying the wrapper down along the adjacent side of the wrapper as the article is lifted alongside the same, and means actuated by the lifter table for lifting and lowering said rod.

18. In a wrapping machine, the combination with means for clamping a wrapper sheet near one edge, of an article lifter for lifting an article

to be wrapped into said sheet, a floating rod resting on the wrapper between the article and said clamp for carrying the wrapper down along the adjacent side of the wrapper as the article is lifted alongside the same, and mechanism actuated by said rod for operating said clamping means.

19. In a wrapping machine, the combination with an article lifter, of means coacting with said lifter to drape a wrapper about the article, a roller coacting with said lifter to lay the wrapper along one side of the article, said roller being mounted for free vertical movement, means on said lifter for imparting movement to said roller, said draping means including a clamp for clamping one edge of said wrapper said clamp being actuated by movement of said lifter table.

20. In a wrapping machine, the combination with an article lifter, a pair of relatively adjustable side plates traveling with said lifter for guiding the articles on said lifter, of a stationary articleway overlying said lifter also having a pair of relatively adjustable side plates for engaging the articles, and connections between the plates on said articleway and said lifter side plates for 25 adjusting the distance between one pair of plates as a result of a similar adjustment of the other pair of plates.

21. In a wrapping machine, the combination with an article lifter, a pair of relatively adjustable side plates traveling with said lifter for guiding the articles on said lifter, of a stationary articleway overlying said lifter also having a pair of relatively adjustable side plates for engaging the articles, and connections between the plates 35 on said articleway and said lifter side plates for adjusting the distance between one pair of plates as a result of a similar adjustment of the other pair of plates, said connections comprising vertical guides secured to one of said pairs of plates, and slides engaging said guides secured to the other pair.

22. In a wrapping machine, the combination with a pair of clamp rollers, means for feeding wrapping material in a position to be clamped 45 by said rollers, mechanism for pushing an article into the clamped wrapping material to be enwrapped by the same, and a brake on one of said clamp rollers controlling the tension required to pull the wrapping material through rollers.

23. In a wrapping machine, the combination with a clamp including a clamp roller, means for feeding wrapping material in a position to be clamped by said roller, mechanism for pushing an article into the clamped wrapping material to 55 be enwrapped by the same, and means on said clamp roller controlling the tension required to pull the wrapping material through the clamp, said means comprising a frictional brake, and means for adjusting the brake pressure of said 60 brake.

24. In a wrapping machine, the combination with a lifter table, of means for feeding articles onto said table, a backing plate against which said articles are fed having a yielding movement 65 in response to the feeding movement of said article, said backing plate tending normally to exert an opposing resistance effective in a sense directly opposite to said feeding movement, and adjustable frictional means resisting movement 70 of said plate, a wrapper guideway on said lifter table, and paper feeding means coacting with said guide to spread a wrapper in position to be gripped between said plate and article.

25. In a wrapping machine, the combination 75

- with a lifter table, of means for feeding articles onto said table, a backing plate having a roughened surface against which said articles are fed and having a yielding movement in response to the feeding movement of said article, and frictional means for varying the resistance of said plate to said movement, said means comprising a friction brake, and devices for varying the braking effect thereof.
5. 26. In a wrapping machine, the combination with a lifter table, of a movable back tension plate on said lifter table, means for feeding an article to be wrapped against said plate, paper feeding means for feeding a wrapper between said article and said plate to be clamped between the article and the plate and a series of serrations on said plate to prevent slippage between said article and said plate during subsequent wrapping operations whereby a uniform lap is obtained.
10. 26. In a wrapping machine, the combination with a lifter table, of a movable back tension plate on said lifter table, means for feeding an article to be wrapped against said plate, paper feeding means for feeding a wrapper between said article and said plate to be clamped between the article and the plate and a series of serrations on said plate to prevent slippage between said article and said plate during subsequent 15 wrapping operations whereby a uniform lap is obtained.
15. 27. In a wrapping machine, the combination with a lifter table, of a movable back tension plate on said lifter table, means for feeding an article to be wrapped against said plate, paper feeding means for feeding a wrapper between said article and said plate to be clamped between the article and the plate and a series of serrations on said plate to prevent slippage between said article and said plate during subsequent 20 wrapping operations whereby a uniform lap is obtained, said serrations taking form of a series of ribs.
20. 27. In a wrapping machine, the combination with a substantially horizontal articleway, of a lifter table movable to and from alignment with said way at one end thereof, means coacting with said lifter table to associate an article and a wrapper, with the wrapper extending about the article with a projecting edge portion thereof hanging below the article, when the lifter is in alignment with said way, means for pushing the article from said lifter onto said way whereby the adjacent end surface of the way folds the hanging wrapper end under the article, and means for exerting a drag of various intensities on and thereby varying the tension with which said hanging wrapper portion is drawn about the article, said last-named means including a swinging apron at and below said end of the articleway, and a co-operating friction roller mounted 25 on the lifter below the edge of said lifter across which the loaf is transferred to the articleway, and means to set said apron at will in various angular positions relatively to said friction roller.
25. 28. In a wrapping machine, the combination with a substantially horizontal articleway, of a lifter table movable to and from alignment with said way at one end thereof, means coacting with said lifter table to associate an article and a wrapper, with the wrapper extending about the article with a projecting edge portion thereof hanging below the article, when the lifter is in alignment with said way, means for pushing the article from said lifter onto said way whereby the adjacent end surface of the way folds the hanging wrapper end under the article, and means 30 for varying the tension with which said hanging wrapper portion is drawn about the article comprising a coacting presser pressing said hanging wrapper portion against said surface, and means varying the pressure between said plate and said presser.
30. 31. In a wrapping machine, the combination with a substantially horizontal articleway, of a lifter table movable to and from alignment with said way, at one end thereof, means coacting with said lifter table to associate an article and a wrapper therewith with the wrapper extending about the article with a projecting edge portion thereof hanging vertically below the article, when the lifter is in alignment with said way, means for moving the article from said lifter onto said way whereby the adjacent edge of the way folds the hanging wrapper end under the article, and means for varying the tension with which said hanging wrapper portion is drawn about the article comprising a plate adjacent said edge and a coacting roller gripping said hanging wrapper portion, and a spring urging said presser and 35 plate together.
35. 32. In a wrapping machine, the combination with a substantially horizontal articleway, of a lifter table movable to and from alignment with said way at one end thereof, means coacting with said lifter table to associate an article and a wrapper therewith with one end of the wrapper under the article and with the wrapper extending about the article with the other end portion thereof hanging vertically below the article, when the lifter is in alignment with said way, means for pushing the article from said lifter onto said way whereby the adjacent end surface of the way folds the hanging wrapper end under the article to lap the first mentioned end, means for exerting tension on the wrapper end to hold the same snugly about the article, and a heater adjacent said articleway end surface for tacking together the overlapped wrapper portions under the article while the wrapper end is still under tension.
40. 33. In a wrapping machine, the combination with a lifter table, of means for feeding articles onto said table, a backing plate against which said articles are fed and having a yielding movement in response to the feeding movement of said article, frictional means for producing a drag on the movement of said plate.
45. 34. In a wrapping machine, the combination with a lifter table, of means for feeding articles onto said table, a backing plate against which said articles are fed and having a yielding movement in response to the feeding movement of said article, frictional means for producing a drag on the movement of said plate, and devices for regulating the amount of drag produced by said 45 frictional means.
50. 35. The combination with an article lifter, of a tension plate on said lifter, said lifter being provided with guide rails and a stationary slotted drag slip, and said tension plate being provided 55 with a carrier slidably mounted in said rails, an extension carrier fitted into the slot of said strip, and a friction shoe mounted on said extension and bearing against one side of said strip, and a spring pressing said shoe against said strip.
55. 75

36. In a wrapping machine, the combination with means for associating wrapping material with an article to be wrapped, of means for feeding said material into the range of action of said associating means, including a roll in feeding engagement with said material, mechanism including a friction clutch operating periodically to intermittently drive said roll, and brake means actuated by said mechanism preventing overrunning of the roll.

37. In a wrapping machine, the combination with means for associating wrapping material with an article to be wrapped, of means for feeding said material into the range of action of said associating means, including a roll in feeding engagement with said material, mechanism operating periodically to intermittently drive said roll, and brake means actuated by said mechanism preventing over-running of the roll, said mechanism including a part having a to and fro motion operating in one direction to drive the roll and a connection between said part and said brake to operate the brake near the end of the driving motion.

38. In a bread loaf wrapping machine, the combination with mechanism for wrapping the loaves, a loaf feed for feeding loaves into said mechanism including an endless conveyor carrying loaf engaging flights and a crumb tray under parts of said mechanism from which crumbs fall, positioned adjacent the path of return movement of said flights to be swept by the flights.

39. In a bread handling machine, the combination with mechanism for performing operations on the loaves of a loaf feed for feeding loaves into said mechanism, including a loaf pusher, a carrier for said pusher imparting to said pusher an operating motion to said pusher along one path and a return motion along another path, and a crumb tray under parts of said mechanism from which crumbs fall positioned adjacent the path of return movement of said pusher to be swept by the pusher.

40. In a wrapping machine, the combination with an article lifter having vertical to and fro motion, of means for associating a wrapper with an article with the wrapper draped over the top of the article, and with one end of the wrapper held between the article and a lifter part, a clamp relative to which the lifter moves, gripping the wrapper near its other edge, and a floating rod resting by gravity on the wrapper between said article and said clamp to drape the wrapper down, alongside said lifter as the lifter rises, under uniform wrapping tension depending on the weight of the rod, said clamp having means arranged to be engaged by the upper side of the rod as the rod is lifted by the pull on the wrapper of the lifter and article whereby the clamp is held open by the pull on the paper and is permitted to close again when said pull is relieved.

41. In a wrapping machine, the combination with an article lifter having vertical to and fro motion, of means for associating a wrapper with an article with the wrapper draped over the top of the article, and with one end of the wrapper held between the article and a lifter part, a clamp relative to which the lifter moves, gripping the wrapper near its other edge, and a floating rod resting by gravity on the wrapper between said article and said clamp to drape the wrapper down, alongside said lifter as the lifter rises, under uniform tension depending on the weight of the rod, said clamp having means arranged

to be engaged by the upper side of the rod as the rod is lifted by the pull on the wrapper of the lifter and article whereby the clamp is held open by the pull on the paper and is permitted to close again when said pull is relieved, and means actuated by said lifter for positively holding open said clamp when the lifter reaches its uppermost position.

42. In a wrapping machine, the combination with an articleway, of paper feeding means coacting with said lifter to drape a wrapper about the article, a rod coacting with said lifter to lay the wrapper along one side of the article, guides for said rod in which said rod is mounted for free vertical movement along the path of the lifter movement, and means coacting with said guide for adjusting the lower limit of movement of said rod.

43. In a wrapping machine, the combination with an articleway, of paper feeding means coacting with said lifter to drape a wrapper about the article, a rod coacting with said lifter to lay the wrapper along one side of the article, guides for said rod in which said rod is mounted for free vertical movement along the path of the lifter movement, means coacting with said guide for adjusting the lower limit of movement of said rod, and means for tucking in the rear end flaps on said article while the lap roller is in substantially its lowermost position.

44. In a wrapping machine, the combination with an article lifter having an up and down movement and carrying a wrapper receiving channel, of a feed for feeding a wrapper into said channel with a portion of the wrapper projecting from the channel, means acting on the projecting portion of the wrapper and coacting with the lifter during movement thereof to spread the wrapper, means for pushing an article into said wrapper and on to said lifter while the lifter is in its lower position with a portion of the wrapper extending over the top of said article and to one side thereof, and a floating element resting by gravity on the portion of the wrapper extending to one side to drape the wrapper down along the adjacent side of said article.

45. In a wrapping machine, the combination with an article lifter having an up and down movement and carrying a wrapper receiving channel, of a feed for feeding a wrapper into said channel with a portion of the wrapper projecting from the channel, means acting on the projecting portion of the wrapper and coacting with the lifter during movement thereof to spread the wrapper, means for pushing an article into said wrapper and on to said lifter while the lifter is in its lower position with a portion of the wrapper extending over the top of said article and to one side thereof, a floating element resting by gravity on the portion of the wrapper extending to one side to drape the wrapper down along the adjacent side of said article, and devices gripping said extending portion of said wrapper on the other side of said element from the article during the upward movement of the lifter.

46. In a wrapping machine, the combination with reciprocating means for yieldingly gripping one end of a length of wrapping material, of mechanism for feeding wrapping material into position to be gripped by said means, a member for pushing an article into the gripped wrapping material to partially enwrap the article therein, whereby the wrapping material will be pulled

from said means and thereby tensioned, and a device for adjusting said means to vary the tension with which the wrapping material is pulled from the same.

5 47. In a wrapping machine, the combination with a vertically movable article lifter having a guide through which wrapping material may be fed, of means for feeding wrapping material through said guide, a device for yieldingly gripping the leading end of the wrapping material fed through said guide to draw the wrapping material from the guide during the downward movement of the lifter, a member for advancing

an article into the wrapping material and on to the lifter when the latter reaches its lower position, said wrapper material feeding means being adjustable to feed various lengths of wrapping material to encompass articles of different 5 girths.

48. In a wrapping machine, the combination with a table of a backing plate yieldingly mounted on said table and movable bodily under frictional restraint to yieldingly oppose the movement of an article on to the same, and a device for varying the frictional restraint of said plate. 10 LESTER FERENCI.
